ADJUSTABLE TABLE AND BENCH

Filed June 16, 1926

UNITED STATES PATENT OFFICE

NOAH S. AMSTUTZ, OF VALPARAISO, INDIANA, ASSIGNOR, BY MESNE ASSIGNMENTS,
TO THE NORTHERN TRUST COMPANY AND HAROLD H. ROCKWELL AS TRUSTEES

ADJUSTABLE TABLE AND BENCH

Application filed June 16, 1926. Serial No. 116,286.

My invention relates to improvements in adjustable tables and benches and it more especially consists of the features pointed out in the annexed claims.

5 The purpose of my invention is to provide tables and benches in different sizes for children or adults; that are simple to make; that are inexpensive; that can be shipped in knock-down condition; that are easily assembled; 10 that are readily adjusted to different heights and that may, if desired, cooperate with educational devices which can be assembled on the table by sliding onto the table top or otherwise. 15 With these and other ends in view I illustrate in the accompanying drawing such instances of adaptation as will disclose the broad underlying features without limiting myself to the specific details shown thereon 20 and described herein.

Fig. 1 is an end view of an assembled table.
Fig. 2 is an end view of a bench.

Fig. 3 is a front view of a table.

Fig. 4 is a cross section in plan of an adjustable leg and connecting clamp.

Fig. 5 is an elevation in section of an adjustable leg in its assembled relation to the top and a foot.

Fig. 6 is a plan view in section of an adjustable leg showing a cross bar attached.

Fig. 7 is an elevation of the related parts in dismembered side by side relation.

In practically carrying out my invention I may use any desired cooperating features 35 which lend themselves to the accomplishment of my purpose. The table top and drawer are the parts which distinguish the table from a bench. All the other parts are substantial duplicates in function and purpose, 40 varying only in dimension and minor changes in shape. In fact, the bench parts, excepting the seat, are substantially duplicated in the table. Because of this overlapping, the same reference numerals are used for similar 45 parts of the table and bench.

In a general sense, I may use any desired shape and size of table top 1. In a restricted sense, when the side edges of the table top 50 are to serve as holding means for a slide-on desk board, then, of course, the width of the

table top will conform to the width of the reinforcing side arms (not shown) of the board. As this slide-on feature is made the subject of a separate application Serial No. 104,252, filed April 24, 1926, it is not further described herein. The table top 1 at its rear edge has a grooved extension 3 which may serve as a pencil rail or also as a groove in which a portable desk may rest as described and set forth in the above referred to copending application. 55

One of the principal purposes of my invention is to provide a table or bench whose component parts may be easily packed in small space for shipment by parcels post while the parts are disassembled. These parts are so arranged that the entire table or bench may be easily set up by an inexperienced person. By reason of this, it is possible to have the tables or benches delivered directly to the user's home at small transportation charges. Another important feature is making the tables and benches adjustable to varying heights and in burying the guiding plates which hold the adjustable portion in proper 60 alignment with the stationary part of the supports. 65

Whether a table top 1 or a bench seat 26 is used, substantially the same under structure is required in both cases, the only real difference being that the parts required for a bench are smaller in size when the bench is to be used with a given size of table. Otherwise, if the bench is to be used independently 70 of the table, its minimum height and length 75 may be whatever the exigencies of actual use may demand. In a similar sense, the table itself may be proportionately increased or decreased in size as desired.

On the under side of the table top 2 or the bench seat 26, side rails 2 are attached by means of screws. When these rails are attached to a table top they have a drawer ledge formed on their inside top corners on which the drawer 6 may slide. When the side 80 rails 2 are ordinarily attached to a seat 26 on a bench to be used with the table, obviously the ledges 5 will be omitted. On the other hand, if a drawer should be desired 85 under the seat of an enlarged bench, it may 90

be supported on ledges 5 formed on side rails 2 in a similar manner to the use made of such ledges on the table.

The side rails 2 are mortised at 4 to receive the tenons 8 of the sliding support 7. These parts may be glued to each other or permanently secured in any other manner. The sliding supports 7 have holes 10 by means of which the table top may be held at different heights on the table legs 13 and 13a. Guide plates 9 are driven into lengthwise grooves formed in the edges of the support 7. These guide plates slide in grooves 14 of the legs 13 and 13a, which construction leaves the outside faces of the supports 7 and the legs 13 and 13a flush with each other. The upper ends of the legs 13 and 13a are drawn toward each other against the sliding supports 7 by means of clamps 19. These clamps are U-shaped so as to permit the legs 13 and 13a and the support 7 to be positioned between the side members of the clamps. The clamps 19 are pivoted at 20 to the extreme upper ends of the legs 13a and are provided with clamping thumb screws 21 which are seated in bushings 22 that are imbedded in the upper ends of the legs 13. Bolts 23 pass through openings 10 of the supports 7 and through suitable openings in the clamps 19 so as to firmly hold the table in different height adjustments. Wing nuts 24 on the outer ends of the bolts 23 serve to hold the bolts 23 in position. These bolts have square shoulders under the heads which engage slots in the clamps 19 and are thus prevented turning while the wing nuts 24 are put into place.

The feet 11 for the table legs are mortised at 12 to receive the tenons 16 of a pair of legs 13 and 13a. They are joined at their lower ends by tie blocks 15 which may be permanently secured to the legs by gluing, the use of corrugated fasteners 27 or they may be held rigidly connected to each other in any other manner. When so assembled, a pair of legs 13 and 13a with a tie block 15 comprise a single unit to be assembled with a single foot 11 by means of the tenon 16 entering the mortise 12 where the parts are permanently attached to each other by gluing or otherwise.

The use of clamps 19 overcomes and avoids the necessity of extreme close fitting of the supports 7 and the table legs. In addition, all tendency to "wobble" of the supports 7 in the legs, is overcome through the use of the clamping screws 21. In the steps of manufacture the grooves 14 on the inner edges of the table legs are usually sawed throughout their length and, if desired, short metal plates similar to the guide plates 9, may be inserted in the grooves 14 at the lower ends of the legs and such short length plates may enter grooves formed in the blocks 15, if such additional reinforcing is desired.

A pair of feet 11 are held spaced apart by a foot rest or cross member 17, the ends of

which are seated in vertical gains 25 formed in the tie blocks 15 where the parts are held in assembled relation by screws 18.

In knock-down shape, the table top 1 is separated from the under rails 2. A rail 2 and a support 7 form one of a pair of units; a pair of legs 13, 13a and a foot 11 form one of a pair of leg units, while the drawer 6 and the cross member 17 form independent units. All of these may be packed together in small space and placed in a carton to be sent by parcel post or otherwise.

If desired, side springs may be attached to the drawer as shown in Fig. 7 to overcome any tendency to slide too freely should the table top be made tilting on sliding supports 7. While the top 1 and rails 2 are shown permanently attached to the supports 7, I do not limit myself to this construction.

In order to produce a finished appearance to the holes 10, eyelets shown in Fig. 4 may be used if desired.

What I claim is:

1. As a new article of manufacture, a pair of legs, a tie block for joining the legs edge to edge against the block at the lower end of the legs, said legs having grooves lengthwise thereof on their adjacently facing edges, a sliding member positioned between the legs having companion grooves in its edges, thin metal plates in pairs of adjacent grooves, a foot for the joined end of the legs permanently attached thereto, and means at the free ends of the legs adapted to adjustably draw the sliding member and legs toward each other.

2. A knock-down article of manufacture comprising a suitable top, a pair of attachable and detachable supports for the underside of the top, a pair of bifurcated legs for each one of the supports, a tie block at the bottom end of a pair of legs, a cross member for holding the legs in spaced apart relation, means on the free ends of each pair of legs for adjustably holding a support in engagement therewith, and means for holding the several parts in assembled relation on a separate foot for each pair of legs.

3. An article of manufacture comprising a sliding member, a thin metal guide plate imbedded in each edge of the member lengthwise thereof, a pair of legs provided with grooves on each edge for the guide plates, a tie block for permanently holding the legs in spaced apart relation at one end thereof, and means at the free ends of the legs for adjustably holding the legs in engagement with a sliding support.

4. An article of manufacture comprising a pair of legs held in spaced apart relation at one end by a tie block, a clamping member pivoted to the upper end of one of the legs, a hard recessed seat in the upper end of the other leg, and an adjusting screw in the clamp engaging the recess.

5. In knock down tables and benches, a separate top, a separate pair of side rails on which the top rests each rail being attached to a slidable support, a pair of legs for each 5 of the slidable supports, a tie block for each pair of legs to hold them spaced apart, the tie blocks having a vertical gain on one face of each block, a separate foot for each pair of legs, grooves formed in the adjacent edges 10 of the support, the tie blocks and the legs, separate guide plates positioned in the grooves, a separate cross member secured in the gains of the tie blocks positioned near the lower ends of each pair of legs for holding 15 them spaced apart, means for securing the side rails to the top and the cross member to the tie blocks, a separate clamp attached to the upper end of each pair of legs, cooperating means comprising bolts engaging the clamps and slidable supports for holding the top in 20 different fixed elevations, and means on the clamps for holding each pair of legs and a slidable support in firm engagement with each other.

25 In testimony whereof I affix my signature.
NOAH S. AMSTUTZ.
